CARBURETOR

Don Cole, Evanston, Ill., and Leonard E. Bogue,
South Bend, Ind.; said Bogue assignor to
Bendix Stromberg Carburetor Company, South
Bend, Ind., a corporation of Illinois

Application March 18, 1931. Serial No. 523,476

3 Claims. (Cl. 261—72)

This invention relates to carburetors and more particularly to a means for venting the carburetor float chamber bowl.

An object of the invention is to vent the float chamber in a manner to subject it to the pressure present in the carburetor air intake horn.

Another object is to provide a carburetor with an air vent which may be formed in the carburetor body.

10 Another object is to provide a carburetor with float chamber vent passages that may be formed in mating surfaces of the carburetor body units.

A feature of the invention relates to a passage in the throttle body portion which partially encircles the mixing chamber and connects the float chamber with the air horn. The passage is preferably formed in the shape of a groove on the under side of the throttle body surface which forms a closed conduit when the main body and 20 throttle body are in their assembled position.

Other objects and features of the invention will be apparent from the following description of one embodiment which I have illustrated in the accompanying drawing in which:

25 Figure 1 is a side elevation partly in section of a carburetor showing the improved float chamber venting; and

Figure 2 is a sectional view taken on lines 2—2 of Figure 1 showing the extent of the venting groove in the throttle body.

Referring to the drawing, 10 is a carburetor having a throttle valve 12, a float chamber 14, and an air intake horn 16'. Float chambers are normally vented to the atmosphere, but it has been found desirable in some cases to have the pressure in the float chamber bowl equal to that existing in the carburetor air horn so that the differential in pressure between the mixing chamber 16 and the float chamber bowl is not changed by restrictions such as air cleaners and silencers which are sometimes installed at the air horn entrance. It is also desirable at times to have the pressure in the float chamber bowl increased with the air flow and for that reason, I prefer 40 to arrange the intake from the air horn in a plane perpendicular to the air flow whereby the kinetic pressure will be transmitted from the air horn to the float chamber.

In the embodiment illustrated, a pipe 18 projects downwardly into the air horn with its entrance in a plane at right angles to the air stream and connects at its upper end with a cored opening 22 in the lower or main body portion 24 of the carburetor. The throttle body portion 26 is provided on its under surface with a

groove 28 which partially encircles mixing chamber 16 and connects with an opening 30 formed adjacent the float chamber bowl and is in communication therewith by means of pipe 32. A gasket 34 is preferably positioned between the two body portions of the carburetor to form a tight closure and if desired, a screw 36 may be used to lock tube 18 in position.

It may be readily seen from the above description that we have provided a venting conduit for 65 a float chamber 14 in which both the static and kinetic pressures existing in air horn 16 are transferred through an integral conduit around mixing chamber 16 to the float chamber 14.

While we have illustrated and described a preferred form of the invention, it is understood that this showing and description are illustrative only, and that we do not regard this invention as limited to the form shown and described, or otherwise, except by the terms of the following claims: 75

We claim:

1. A carburetor comprising, a main body portion having a float chamber and an air horn, said air horn having a passageway terminating in the upper surface of the body portion, a throttle body portion having a groove in its lower surface overlapping said passageway and forming a conduit between the passageway and float chamber. 80

2. A carburetor comprising a main body portion having a float chamber and an air horn, a throttle body portion having a mixing chamber, said throttle body portion having an arcuate groove forming with the main body portion a conduit around the mixing chamber and inter- 85 connecting the air horn and float chamber.

3. A carburetor comprising a body section having a float chamber and an air horn, an air conduit having an inlet in the air horn, and a second body section having a throttle, one of said 90 body sections being formed with a groove cooperating with a surface of the other section to form a connection between the conduit and the float chamber. 95
